(57) **CLAIM**

The ornamental design for a HEPA door, as shown and described.

DESCRIPTION

FIG. 1 is a front elevation view of a HEPA door;
FIG. 2 is a back elevation view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a front top left perspective view thereof;
FIG. 8 is a back top left perspective view thereof; and,
FIG. 9 is a front elevation view of a HEPA door, showing attached environmental structure.

The broken lines are for environmental purposes only and form no part of the claimed design.

1 Claim, 5 Drawing Sheets
